UNITED STATES PATENT OFFICE

HANS SCHULTHEISS, OF BALTIMORE, MARYLAND

APPLICATOR

Application filed May 8, 1931. Serial No. 535,982.

This invention relates to improvements in applicators, and more particularly to devices of this character adapted for ready attachment to the threaded nipple of a collapsible paste tube; the collapsible tube functioning as a handle for the applicator, and as a convenient means for supplying a paste, such as shaving cream, to the working surface of the applicator.

10 Specifically, the invention relates to improvements in the construction of devices of this character, and has for an object to provide an applicator for collapsible tubes having a flared, concaved paste distributing and 15 working surface, whereby a beard softening medium, such as shaving cream, may be uniformly spread over the beard surface of the face and the coated surface massaged as the cream is dispensed from the tube.

20 A further aim is the provision of spaced cream ducts or ports leading from within the cap-like fitting of the applicator to the lowermost point of the concaved working surface, the ducts or ports being disposed to 25 each side of the longitudinal center of the working surface and flared towards the outer end thereof.

A still further object of the invention consists in the provision of an outwardly flared 30 concaved paste or cream applicator, the working surface of which is provided with a fan-like series of relatively shallow grooves and intermediate ribs which merge with the concaved working surface adjacent its lowermost point. Other objects and purposes will 35 also appear hereinafter.

An exemplification of this invention is set forth in the accompanying drawings in the manner following:

40 Fig. 1 is a rear perspective view of my improved applicator as applied to the threaded end of the collapsible tube and showing the manner of directing the applicator over the surface to be coated;

45 Fig. 2 is a side elevation of the assembly

shown in Fig. 1, the applicator being shown in section;

Fig. 3 is a top plan view of the applicator applied to a collapsible tube;

Fig. 4 is a transverse section taken on line 4-4 of Fig. 3; and

Fig. 5 is a view similar to Fig. 3, of a slightly modified form of the invention.

In the drawings the portion indicated as A represents a collapsible paste tube of usual construction and design having a threaded nozzle or nipple B through which the contents of the tube may be discharged.

The applicator, designated broadly as 5, comprises a substantially triangular plate 60 having rounded corners and from the inner corner of which depends an interiorly threaded cap-like fitting 6 adapted to be screwed to seated position on the nipple B of the collapsible tube A. In this position of parts the tube A functions as a handle for the applicator 5, as shown in Fig. 1, and also as a means for supplying cream under pressure to the chamber 7, thence through the ducts or ports 8 and 9 to the working surface 10 of the applicator.

To facilitate uniform distribution of the paste or cream discharged through the ports 8 and 9 to the working surface 10 of the applicator, the plate is outwardly flared and slightly dished or concaved from a point inwardly of the ports 8 and 9 to the outer flared edge thereof.

The inner end portion 11 of the plate immediately above the threaded fitting 6 is preferably formed flattened and slightly elevated above the major portion of the plate to provide a sliding bearing surface or pivotal base for controlling the operation of the applicator thereabout when pressed firmly against the bearded surface of the face and moved thereover.

By the construction just described the dished or concaved portion 10 of the applicator, which is outwardly flared from the

relatively small and flattened bearing surface 11 and handle connecting fitting 6, may be readily maintained in contact with the bearded surface of the face under a desired pressure, or in slightly spaced relation thereto and 5 shifted from side to side during movement in following the contour of the face.

As a further means for uniformly distributing a beard softening medium over the 10 surface to be treated and massaging the coated surface as the applicator is moved thereacross, I have provided a fan-like series of relatively shallow grooves 12 and intermediate ribs 13 which extend inwardly from the 15 outer flared edge of the plate to a point inwardly of the ports 8 and 9 where the grooves and ribs merge with the concaved wall of the working surface 10.

While a device constructed according to 20 the present detailed description may be produced at small expense and assembled with little effort, I do not desire to be specifically limited thereby since many changes and modifications may be made by those skilled 25 in the art, without departing from the spirit and scope of my invention, as covered by the appended claims.

I claim:

1. An applicator adapted for attachment 30 to the discharge nozzle of a collapsible tube or the like, comprising a spreading plate having a sliding bearing surface adjacent one end thereof for controlling the movement of the plate relative to the surface being coated and 35 said plate having longitudinal side flanges extending from the sides of said bearing surface and projecting above said spreading plate.

2. A device for applying shaving creams 40 or other beard softening medium, comprising an elongated spreading plate having a sliding bearing surface at one end thereof, an interiorly threaded cap-like fitting depending from the underside of said plate, said 45 plate having a transverse series of ribs on its upper surface extending from a point adjacent the bearing surface to its unrestricted opposite end and ports leading from said surface to the interior of said fitting.

50 3. A device for applying shaving creams or other beard softening medium, comprising a substantially triangular plate, an interiorly threaded cap-like fitting depending from the underside of said plate adjacent 55 one corner thereof, the upper surface of said plate being flattened immediately above said fitting and constituting a sliding bearing surface, and outwardly flared and concaved from said flattened portion and providing 60 converging side flange portions, the concaved surface of said plate having parts leading to the interior of said fitting.

4. A device for applying shaving creams or other beard softening medium comprising 65 a cap-like fitting having a bore adapted for

attachment to the discharge nozzle of collapsible tubes, said fitting being formed with an elongated spreading plate having a sliding bearing surface adjacent one end, an unobstructed delivery portion at its opposite end, said plate being further formed with upturned side edge portions and a port extending from said plate between the upturned portions and communicating with the bore of the fitting.

In testimony whereof I affix my signature.
HANS SCHULTHEISS.
